UNITED STATES PATENT OFFICE.

ARCHIBALD KIRK AND SAMUEL L. BRIERLY, OF BEAVER FALLS, PENNSYLVANIA,
ASSIGNORS TO K & B COMPANY, OF BEAVER FALLS, PENNSYLVANIA, A CORPORA-
TION OF PENNSYLVANIA.

WALL-PAPER-DISPLAY PANEL.

Application filed November 6, 1925. Serial No. 67,242.

This invention is for an improvement in a panel adapted especially for the display of samples of wall paper, but equally applicable to the display of posters, placards, fabrics, 5 and the like, as may be desired.

In the selling of wall paper in retail stores, it is a common practice to display samples of paper, with or without samples of borders, 10 ceilings, binders or other trimmings, on a panel by means of which the general appearance and effect of the paper may be shown to the best advantage. Such panels are usually hinged along the wall so that a customer may leaf through them in making a selection. 15 In panels heretofore provided for this purpose, it has been necessary to paste the samples in the panel and this requires considerable time and care and makes replacement difficult. 20 It also happens that during a busy season, a particular pattern of paper will become exhausted during the course of a day, and since the sample cannot be readily removed or covered by another sample, it must remain 25 on exhibition until the dealer may have an opportunity to take the time to remove it from display. It will frequently happen that a prospective customer will, upon seeing the sample of the exhausted paper, want it to 30 the exclusion of any other pattern, and being unable to obtain it, will go elsewhere; whereas, were it possible to immediately remove such sample, that customer, not having seen the exhausted paper, would make a selection 35 from such paper as remained in stock.

According to the present invention it is proposed to provide a display panel wherein samples of paper can be placed and removed in a short space of time without the use of 40 paste and without requiring any special tools, fasteners or tacks, and wherein the paper will be held neatly and smoothly.

While we describe our invention specifically in connection with the display of wall paper, it can be applied with equal advantage and facility to the display of sheets of various kinds of materials, posters, news bulletins, 45 placards, etc.

The invention may be readily understood 50 by reference to the accompanying drawings, wherein:

Figure 1 is a front elevation of the panel,

Figure 2 is a side view thereof; 55
Figure 3 is a transverse section on the line III—III of Figure 2;

Figure 4 is an enlarged detail view of one corner of the panel;

Figure 5 is a perspective view of a form of metal corner clip used on the panel and comprising part of the present invention; 60 and

Figure 6 is an enlarged end view of one corner of the panel.

In the drawings, 5 designates a suitable base member or panel. It may be of wood, 65 fibre-board, composition, or any suitable material. When the invention is to be adapted to the display of wall paper, it is of a dimension suitable to the standard size of wall paper. 70

Along each of the longitudinal edges of the panel are hinged strips 6 and along the ends are hinged strips 7. In order to present a neat and finished appearance, the strips are mitered at the corners, as indicated at 9. 75

The mounting of the strips is accomplished by any suitable means or fixtures. We prefer to use a fixture which shall support strips on opposite faces of the panel, and will also provide a socket for the pintle of a hinge to 80 permit of the panel having a swinging support when so desired. As an example of such a fixture, reference may be had to Figures 4, 5 and 6, which show such a fitting in detail. 85

The fitting, designated generally as 10, is formed integrally from a piece of sheet metal, and has spaced apart strap portions 11 that straddle the panel, and which may be suitably perforated to permit securing means to pass 90 therethrough. The strap portions are connected by a loop portion 12 which is necked-in at 13 to provide a pintle socket. Portion 12, of course, projects beyond the edge of the panel. On each of the strap portions 11 is a wing 14 perpendicular thereto and which has a second wing 15 formed thereon at right angles to wing 14 and also at right angles to strap portion 11. 95

When the fitting is applied to the panel, 100 wings 14 and 15 are perpendicular to the face of the panel and at right angles to each other. The fitting shown in Figure 5 is in the position corresponding to the fitting in the upper

right hand corner of Figure 1. By turning the fitting about, it is adaptable to any of the four corners.

Each wing has an inner hole 16 and an outer hole 17 therein. A screw 18 entered in the outer hole 17 passes longitudinally into the strips 6 or 7, providing a pivoting or hinged support therefor. Each strip 6 or 7 preferably carries at one or both ends a spring projected snap or detent pin 19 which normally engages the inner hole 16 to hold the strips 6 or 7 in normal closed or paper clamping position.

Ordinarily the strips 6 and 7 are in the position shown in Figures 1 and 2, wherein they lie flat on the surface of the panel. When it is desired to secure a strip of wall paper, or samples of wall paper in place, assuming that wall paper is to be displayed, the strips are swung transversely of their lengths on screws 18 as pivots to the position of strip 6 in Figure 6, or to the dotted line positions in Figure 3. A piece of wall paper is then laid on the panel, this piece of paper being of such dimension that when the strips are swung back to normal position the ends and edges of the paper will be under the edges of the strips. When the paper has been laid in place, the strips are swung back to normal position. The strips then overlie the paper and clamp it on the panel. In Figure 4, the broken lines A indicate the edges of a sheet of paper so held.

It is not necessary that in all cases the paper be held along four edges, as sometimes it is sufficient that only the side edges be held, as will be readily understood.

With an arrangement such as this, a sample of wall paper, a poster, or other sheet to be displayed may be readily inserted or removed from the panel. In the case of wall paper, the panel would be of a standard width and a dealer would only have to tear or cut a strip of paper to length and mount it on the panel. Since the edges of the paper are concealed, neither the sides nor ends need be trimmed to present a neat appearance. If a border is to be displayed with the sample

of paper, it can be laid crosswise of the panel with its side edges, or side edges and top edge, alone under the clamping strips. Different papers can be displayed on opposite faces of the panel and the paper on one side can be replaced without disturbing the paper on the other side.

While we have shown and described in detail a preferred embodiment of the invention, various changes and modifications are contemplated within the scope and spirit of our invention.

We claim:

1. A display panel of the class described, including a base member, a strip along each edge of the base member on each face thereof, said strips on each face intersecting near the corners thereof, and a fixture at each corner of the base having means thereon for pivotally supporting the intersecting strips on each face of the base, said fixtures also having a hinge extension thereon through which a pintle for hingedly supporting the panel may be passed.

2. A display panel comprising a base, clamping strips on opposite faces of the base, and a fixture connected to the base having portions projecting from the opposite faces thereof and providing pivotal support for clamping strips on opposite faces of the base.

3. A display panel comprising a base, clamping strips on opposite faces of the base, and a fixture connected to the base and extending around an edge thereof, such fixture providing pivotal support for clamping strips on opposite faces of the base.

4. A display panel comprising a base, clamping strips on opposite faces of the base, and a fixture connected to the base and extending around an edge thereof and supporting clamping strips on opposite faces thereof, and means on the fixture for engaging supporting means for the panel.

In testimony whereof we have hereunto set our hands.

ARCHIBALD KIRK.
SAMUEL L. BRIERLY.
